SCREW

Warren Frederick Flesselles, Potts Point, near
Sydney, New South Wales, Australia

Application October 15, 1931, Serial No. 569,040,
and in Australia October 15, 1930

1 Claim. (Cl. 85—45)

This invention relates to improvements in screws for wood or metal operable by a screwdriver.

It is well known that owing to defects in screwdrivers and the tendency of a person to turn a screwdriver other than in a purely radial manner, the screwdriver is frequently forced out of the usual transverse slot provided in the head of screws of the above kind.

An object of the present invention is to provide a screw which will obviate or minimize the above defects and ensure that the screw is inserted and withdrawn in a more expeditious manner.

According to the invention the head of the screw which may be of the countersunk, cheese head, or other type, is provided with a slot for engagement by a screwdriver. The slot is unlike that usually provided in that it has a central stop or abutment which is formed by displacing some of the metal adjacent to the slot and is adapted to be bridged by the operative face of the screwdriver, said screwdriver being provided with a gap to receive the abutment.

The abutment divides the slot in the screw centrally, and by engagement with the gap provided in the screwdriver blade tends to prevent lateral movement thereof with respect to the screw, with the result that the tendency of the blade to leave the said slot is eliminated.

In order that the invention may be more readily understood reference will now be made to the accompanying drawing wherein:—

Figure 1 is a plan view of my improved screw showing the central abutment.

Figure 2 is an elevational view of the head of my improved screw also showing the central abutment.

Figure 3 is a longitudinal sectional view in perspective showing on an enlarged scale, the manner in which portion of the metal forming the head of the screw has been pressed into the slot to form an abutment which is adapted to be engaged by a gap disposed centrally in the screwdriver blade.

Figure 4 is a detail view illustrating how a screwdriver blade may have a gap formed therein so as to bridge the abutment.

Figures 5 and 6 illustrate the preferred method adopted for forming the abutment across the slot in the screw. Figure 5 shows a die preparatory to descending upon the head of the screw and Figure 6 shows the head of the screw after the die has descended, and forced some of the metal of which the head is composed, into the slot to form the abutment.

The slot 7 for engagement by the screwdriver may be formed by milling or stamping in the usual manner after which operation it is necessary to produce the abutment 8 centrally of the slot 7.

I have found that the most convenient manner of forming the abutment is to displace into the slot 7 some of the metal, from the head 9 of the screw.

The abutment 8 as seen in Figure 3 is formed by two portions or lugs 10 of metal which have been pressed into the slot 7 by means of a die such as that diagrammatically represented at 11 in Figures 5 and 6. The die 11 leaves a space 12 in the head of the screw the depth of which is less than the depth of the slot 7.

Having determined upon the size of the abutment 8, the length and width of the die 11 and the extent to which it is forced into the head of the screw, can easily be determined by calculating the volume of metal desired to form the abutment 8.

The screwdriver used with the present invention will require to have a gap such as that indicated at 13 in Figure 4.

I claim:

A screw comprising a threaded stem, a slotted head integral therewith and provided with a top face, and a narrow abutment formed in the slot in said head and constituted by two narrow projections disposed centrally in and transversely of said slot, said projections being spaced from the top face of the screw head and in the direction of the bottom of the slot, and consisting of equal portions of metal forced from the opposed walls of said slot.

WARREN FREDERICK FLESSELLES. 95
